UNITED STATES PATENT OFFICE.

RICHARD C. BRADLEY, OF CHICAGO, ILLINOIS, ASSIGNOR OF ONE-HALF TO FRED J. BRADLEY, OF CHICAGO, ILLINOIS.

COUNTING WHEEL FOR INTERMITTENT-GEAR TRAINS.

1,404,340.

Specification of Letters Patent. Patented Jan. 24, 1922.

Application filed December 6, 1918, Serial No. 265,655. Renewed August 23, 1921. Serial No. 494,735.

To all whom it may concern:

Be it known that I, RICHARD C. BRADLEY, a citizen of the United States, residing at the city of Chicago, in the county of Cook and State of Illinois, have invented certain new and useful Improvements in Counting Wheels for Intermittent-Gear Trains, of which the following is a specification.

My invention relates to devices for counting and indicating or registering a series of operations which are caused to actuate the device, and it has particular relation to those in which an indication or registration is made by means of intermittently acting gears constituting what is commonly known as a Geneva movement. My invention provides means by which the movements of successive indicating wheels or discs are communicated to each other by simple mechanism; by which they are securely locked in relation to each other at intermediate periods of their operation, and by which the wheels or counters may be made in a very simple and inexpensive manner.

The principles of my invention are illustrated in the drawings, in which—

Fig. 1 shows a front view of a meter embodying the principles of my invention;

Fig. 2 is an elevation of one face of my improved disc or counter showing the driving teeth;

Fig. 3 is an elevation of the other face of such gear or counter showing the driven teeth;

Fig. 4 is an enlarged vertical section of such gear or counter;

Fig. 5 is a perspective of a connecting pinion.

Further describing my invention with reference to the drawings, in which like characters of reference denote like parts throughout: 1 is the base, 2 the casing, 3 the cover, and 4 the dial of a meter, the several portions being broken away to show the inside mechanism. On the frame 5 is mounted the driving wheel 6, which is externally actuated. 7 is the shaft thereof on which is the worm gear 8, meshing with the spur gear 9. The latter is mounted on shaft 10 and rigidly attached to the unit counting wheel 11 of the train.

The construction of the intermediate wheels of such train is shown in Figs. 2, 3 and 4. They comprise two elements, prefer-

ably formed from sheet metal, which respectively act as the driving and driven members of the wheel. The latter member is shown in Figs. 3 and 4, and includes the face 15, the hub 16, the teeth 17, extended outwardly into a plane external to the face, and the right angled flange 18 turned in a direction opposite to that of the teeth. The face of the flange is adapted to receive indicative numbers or characters as shown in Fig. 1, and the uniform edge 18' thereof forms one side of a groove as hereafter explained. The said teeth are attached at the bases 19 thereof and the body portions 20 are set out from the face of the member a distance preferably substantially equal to the thickness of the metal from which it is formed, and they are not extended to the periphery, but leave an annular space 21 adjacent thereto.

The other or driving member is shown in Figs. 2 and 4, and comprises the face 25, the hub 26, the teeth 27 turned in one direction, and the right angled annular flange 28 turned in the other direction. The said flange is of substantially the same width as that on the other member, and it is of such size that it will be rigidly received therein. As the edges of the inside flange bear on the inside face of the other member a projecting or locking-ledge or shoulder 30 is provided adjacent to the edge 18' or flange 18, forming therewith a groove or guideway 31. The teeth as shown are two in number. They are off-set from the body of the material, substantially the thickness thereof, and they should extend to the line of the locking-ledge 30. But opposite thereto and to the space between them the flange 23 should be cut away at 29 so that the shoulder or locking-ledge 30 is interrupted at that point.

A stationary shaft 35 is secured to the frame and between each pair of counter wheels has loosely mounted thereon a pinion 36, shown in enlarged perspective in Fig. 5. It is provided with a series of short teeth 37 of such length as to engage the driving and driven teeth of two adjacent counting discs. Alternately therewith are teeth 38 of such additional length that they may engage and ride on the locking-ledge 30, while longitudinal motion on the shaft is limited by the flange edge 18' on the one hand and by the peripheral space 21 on the

other. It will be seen that when two adjacent discs are put in proper relative position and assembled with one of the long teeth of the pinion between driving teeth 27 and the other end between two corresponding driven teeth 20, and the first disc of the train is turned, the pinion will make a partial revolution until said long tooth is freed, so that it rests upon the locking-edge, thereby preventing any relative movement of the driven teeth until said driving teeth 27 of the pinion and the following long tooth is freed from the locking-edge by rotation into the slot 29.

15 It is clear that additional driving teeth 27 may be placed at different peripheral distances around the disc 25 as a greater relative number of rotations of the driven member are desired. It is also apparent that 20 in an apparatus like that shown the driven teeth may be omitted from the first wheel, and the driving teeth from the last wheel of the train.

I claim:

25 1. A constituent counting wheel member formed from a sheet metal blank having teeth cut partially free from and integral with the body portion thereof extended laterally in one direction into a plane substantially parallel to said body portion and provided with a flange turned laterally in the other direction and adapted to be engaged by a corresponding flange on a similarly flanged member.

35 2. A counting wheel having two sheet metal members each provided with teeth struck from the body portion in one direction and with peripheral annular flanges turned in the other direction, the flange of 40 one member being received within the flange of the other member so as to form a groove

between its periphery and the edge of the receiving flange.

3. A counting wheel comprising a sheet metal member provided with a continuous series of teeth struck from the body portion thereof in one direction, and a continuous annular flange turned in the other direction; and a sheet metal member having a pair of teeth struck from the body portion in one direction, and an annular flange interrupted at a point adjacent to said pair of teeth received within the first named flange and forming an annular guideway in combination with the edge of said first named flange.

4. A counting wheel having two sheet metal members, each having teeth struck from the body in one direction, the bases of the teeth extending in a plane transverse to the axis of the wheel, with the major length of the teeth disposed radially of said members, and telescoping peripheral flanges turned in the other direction from the members.

65 5. A counting wheel having two sheet metal members, one of said members having teeth struck from the body in one direction, the bases of the teeth extending in a plane transverse to the axis of the wheel with the major length of the teeth disposed radially of said member and telescoping peripheral flanges turned in the other direction from the members, the outer ends of the teeth terminating inwardly of the periphery of the adjacent member and coextensive with the outer face of the flange of the other member.

In witness whereof, I have hereunto subscribed my name this 25th day of November, 1918, at Chicago, Cook County, Illinois.

RICHARD C. BRADLEY.
